(57) **CLAIM**
The ornamental design for a lap desk with a stuffed dog attached, as shown and described.

DESCRIPTION

FIG. 1 is a top view of the lap desk with a stuffed dog attached, which embodies my design;

FIG. 2 is a bottom view of the lap desk with a stuffed dog attached;

FIG. 3 is a front side view of the lap desk with a stuffed dog attached;

FIG. 4 is a back side view of the lap desk with a stuffed dog attached; and,

FIG. 5 is a side view of the lap desk with a stuffed dog attached.

All broken lines shown in the drawings are for illustrative purposes only and form no part of the claimed design.
